UNITED STATES PATENT OFFICE.

OSKAR K. KLEIN, OF ST. LOUIS, MISSOURI.

LOCK.

1,407,868.

Specification of Letters Patent. Patented Feb. 28, 1922.

Application filed December 4, 1920. Serial No. 428,295.

To all whom it may concern:

Be it known that I, OSKAR K. KLEIN, a subject of the Government of Hungary, residing at the city of St. Louis, in the State of Missouri, have invented certain new and useful Improvements in Locks, of which the following is a specification.

This invention has for its object the provision of a strong lock for motor-vehicles—
10 one that can not be picked and which can not be broken by hammering. This lock is, also, simple and cheap to manufacture and consists of only a few parts. Moreover, it resembles a so-called combination lock and
15 is, in fact, a permutation lock, inasmuch as its setting can be changed, so that it will not operate on its old combination.

This lock is particularly suited to lock a gear-shifting lever of the ball-and-socket
20 type, but may be adapted to other styles.

It is so placed with reference to the floor
of the car that the means of access thereto
is not easily discoverable and, when dis-
25 covered, necessitates a large amount of labor
to reach and remove the control screw.

In the accompanying drawings forming
part of this specification, in which like num-
bers of reference denote like parts wherever
they occur,

30 Figure 1 is a side elevation in connection
with the gear-shifting lever of the ball-and-
socket type;

Figure 2 is a sectional view of the locking
shaft, taken on the line 2—2 in Figure 5;

35 Figure 3 shows the relative combination
of the three parts forming the locking device;

Figure 4 is a top plan view of the lower
or movable locking member;

40 Figure 5 is a sectional view taken on the
line 5—5 in Figure 1, showing the gear-shift
in locked position;

Figure 6 is an enlarged view, showing
more clearly the construction of the station-
45 ary locking member;

Figure 7 shows the U-shaped bar in a re-
tracted or unlocked position;

Figure 8 is a top plan view of the dust-
cap;

50 Figure 9 is a top plan view of the key;

Figure 10 shows the key in position on the
lock;

Figure 11 is a perspective view of a

washer used to lock the movable and sta-
tionary members of the lock together;

55

Figure 12 is a sectional view showing the
relative position of the washer depicted in
Figure 11 and parts locked thereby.

The control screw 1 is located underneath
the device and near the floorboards 2. It 60
screws into the threaded hollow end of the
steel central arbor 3, which is keyed to or
otherwise in fixed connection with the other
parts of movable lock-member 4. The said
arbor 3 is located in hollow shaft 5, which is 65
fastened by pins 6 to nurled casing 7. Shaft
5 is contained within collar or sleeve 8, pref-
erably formed integral with collar or sleeve
9, having the solid or closed end 10, although
if the end were open it would be impossible 70
to tamper with bolt 11 or any other part of
the lock.

Bolt 11 is located and adapted to slide
within collar or sleeve 9, its forked end 12
when in locking position so taking hold of 75
the lower part of gear-shifting lever 13 as to
prevent its movement. It will be seen that
fork 12 and bolt 11 are well protected from
attack by hammering. Collar or sleeve 9 is
threaded into collar or sleeve 14, which 80
surrounds the ordinary casing 14^a inclosing
the lower end of lever 13, and collar or
sleeve 14 is fastened to the said casing by
screws 14^b. A hole is cut in the side of cas-
ing 14^a for the passage of bolt 11.

85

Bolt 11 is made of steel, and bears a rack
15, which is engaged by teeth 16 circumfer-
entially arranged on the lower end of hollow
shaft 5, being preferably cut therein. Ro-
tation of shaft 5 in either direction moves 90
bolt 11 in either direction, and thereby either
locks or unlocks lever 13, according to
whether fork 12 is moved into engagement
or out of engagement therewith. Shaft 5 is
rotated by handgrasp upon nurled casing 7 95
after the lock has been unlocked by key 17.
Bolt 11 is locked in locking or unlocked po-
sition whenever key 17 is removed from the
position shown in Figures 1, 2, and 10.

A hole is formed in the side of collar or 100
sleeve 14, and threads 18 cut therein and on
the outside of the mouth of collar or sleeve
9. Collar or sleeve 8 can be similarly at-
tached to collar or sleeve 9 instead of being
cast integrally therewith.

105

Washer 20 has lugs 21, which fit into

notches 22 in the lower end of arbor 3 and lugs 23 that fit into notches 24 in flange 25 within collar 8, and thereby the movable and immovable lock-members are locked together, screw 1 holding washer 20 in place.

Within casing 7 is formed a shoulder 26, upon which rests notched plate 27 which is fastened to shoulder 26 by screws 28.

Plate 29 is attached to plate 30 by long screws 31 that pass through sleeves 32, adapted to space plates 29 and 30 apart.

In plate 29 is formed a plurality of pockets or recesses 33, each containing a spring 34. An equal number of holes 35 are formed in plate 30. A plug 36 is located in each pocket 33 and hole 35. Each plug 36 is so formed as to bear a wide ward 37 and a narrow ward 38. These are so arranged that the wider wards 37 fit into the scallops or notches 39 in plate 27 whenever key 17 is not in the place shown in Figures 1, 2, and 10. This prevents rotation of casing 7, shaft 5, teeth 16, and the driving by means of rack 15 of bolt 11 to lock or unlock lever 13.

When, however, the fingers or pins 40 on key 17 are inserted through holes 41 in dust-plate 42 and into the holes 35 in plate 30 that are opposite the particular plugs 36 the wide wards 37 of which are caught or held in notches 39 in plate 27, and pressure is applied to key 17, and the same pressed down so that button 43 can be turned transversely of slot 44 in key 17, so as to hold key 17 down against the pressure of springs 34, then the wide wards 37 are pushed out of engagement with notches 39 and the lock can be operated.

The narrow or thin wards 38 will clear notched plate 27 when the thick or wide wards 37 will not. Any one trying to tamper with the lock without the right key would spend infinite time trying all the plugs 36 through holes 41 and 35 to find out which ones needed depressing to clear plate 27. To such person the arrangement and movement of plugs 36 is invisible, and so far as he knows they all act the same. The normal position of wards 38 is out of engagement with plate 27, while the normal position of certain wards 37 is seated in notches 39 of plate 27 and held from lateral movement or rotary movement on the axis of arbor 3 by engagement with plate 27. Insertion of the pins 40 of key 17 in holes 35 adjoining the plugs 36 having their wide wards 37 opposite plate 27 and pressure on the said key 17 presses the said plugs 36 to such an extent as to carry their wide wards 37 out of notches 39 and out of engagement with plate 27, which allows the rotation of casing 7 and arbor 3.

The plugs 36 are so constructed, each with a wide ward 37 and a narrow ward 38, that they may be used either as locking members

or as idlers. Referring to Figure 6, the plugs with the wide wards 37 lowest are locking tumblers, while those in a relatively inverted position are idlers. This relation can be changed at will. In other words, the combination can be changed whenever desired, by simply changing the plugs that present their wide wards 37 opposite to plate 27 when not under pressure from the pins 40 of key 17. The number of possible permutations is very great. The springs 34 and the pockets 33 and the holes 35 are all equally serviceable whether wards 37 or wards 38 are nearest to plate 30. All that is necessary to change the combination is to invert certain plugs 36.

The number of plugs 36 that will usually not be idlers but used as locking members may be varied from one up to as many as may be desired, but five is a very satisfactory number, being neither too simple nor too complex. According to the number of such plugs will be the number of pins 40 on key 17. In order that in use the pins 40 of key 17 may be guided into the right holes 41 and 35, a plurality of pins 44 project from plate 30 through slots 45 in dust-plate 42.

Dust-plate 42 merely keeps dust from entering through holes 35 when key 17 is not in use in the lock, plate 42 being adapted to rotate a short distance in both directions on screw 46, such distance being enough either to cover or uncover holes 35. Knob 47 enables plate 41 to be pushed.

The location of pins or studs 44 need not be changed no matter what combination is arranged, but plate 30 bearing the same can be turned around, so as to make them apply. When the combination is changed, the pins 40 on key 17 must be changed, so as to fit the new combination. Speaking from the standpoint of the factory, each lock will originally be sent out with a combination different from all or many others, and there will be furnished with each lock a key having its pins 40 so set as to fit that lock.

The diameter of both wards 37 and 38 is greater than the diameter of the holes 35.

The slots 45 permit the rotary reciprocating movement of dust-plate 41 notwithstanding the projection therethrough of guidepins 44. Round holes would not do, as they would prevent any movement of plate 41.

Having thus described this invention, I hereby reserve the benefit of all changes in form, arrangement, order, or use of parts, as it is evident that many minor changes may be made therein without departing from the spirit of this invention or the scope of the following claims.

I claim:

1. The combination of a casing having a plurality of sleeves or collars, a recipro-

cable locking member located therein and bearing a rack, a rotatable member located therein and bearing teeth adapted to engage the said rack and to reciprocate the 5 said locking member when the said rotatable member is rotarily reciprocated, a central arbor in fixed relation to the said casing, a casing in fixed relation to the said rotatable member and containing a notched 10 plate, a pair of plates in fixed relation to the said arbor, a plurality of ward-bearing members located between the said plates, some of the said wards being in locking engagement with the said notched plate, and 15 a key adapted to release the said locking engagement.

2. The combination of a casing having a plurality of sleeves or collars, a reciprocable locking member located therein and bearing 20 a rack, a rotatable member located therein and bearing teeth adapted to engage the said rack and to reciprocate the said locking member when the said rotatable member is rotarily reciprocated, a central 25 arbor in fixed relation to the said casing, a casing in fixed relation to the said rotatable member and containing a notched plate, a pair of plates in fixed relation to the said arbor, a plurality of ward-bearing members 30 located between the said plates, some of the said wards being in locking engagement with the said notched plate, springs for maintaining the said wards in the said position, and a key adapted to release the said 35 locking engagement.

3. The combination of a casing having a plurality of sleeves or collars, a reciprocable locking member located therein and bearing a rack, a rotatable member located therein 40 and bearing teeth adapted to engage the said rack and to reciprocate the said locking member when the said rotatable member is rotarily reciprocated, a central arbor in fixed relation to the said casing, a casing 45 in fixed relation to the said rotatable member and containing a notched plate, a pair of plates in fixed relation to the said arbor, a plurality of ward-bearing members located between the said plates, some of the 50 said wards being in locking engagement with the said notched plate, springs for maintaining the said wards in the said position, pockets in one of the said plates adapted to hold the said springs, and a key 55 adapted to release the said locking engagement.

4. The combination of a casing having a plurality of sleeves or collars, a reciprocable locking member located therein and bearing 60 a rack, a rotatable member located therein and bearing teeth adapted to engage the said rack and to reciprocate the said locking member when the said rotatable member is rotarily reciprocated, a central arbor in 65 fixed relation to the said casing, a casing

in fixed relation to the said rotatable member and containing a notched plate, a pair of plates in fixed relation to the said arbor, a plurality of ward-bearing members located between the said plates, some of the said 70 wards being in locking engagement with the said notched plate, and a key adapted to release the said locking engagement, one of the said plates having holes for the insertion of the said key.

5. The combination of a casing having a plurality of sleeves or collars, a reciprocable locking member located therein and bearing a rack, a rotatable member located therein and bearing teeth adapted to engage the 80 said rack and to reciprocate the said locking member when the said rotatable member is rotarily reciprocated, a central arbor in fixed relation to the said casing, a casing in fixed relation to the said rotatable member 85 and containing a notched plate, a pair of plates in fixed relation to the said arbor, a plurality of ward-bearing members located between the said plates, some of the said 90 wards being in locking engagement with the said notched plate, and a key adapted to release the said locking engagement, one of the said plates having holes for the insertion of the said key, and the said key bearing pins adapted to pass through the said 95 holes.

6. The combination of a casing having a plurality of sleeves or collars, a reciprocable locking member located therein and bearing a rack, a rotatable member located therein 100 and bearing teeth adapted to engage the said rack and to reciprocate the said locking member when the said rotatable member is rotarily reciprocated, a central arbor in fixed relation to the said casing, a casing 105 in fixed relation to the said rotatable member and containing a notched plate, a pair of plates in fixed relation to the said arbor, a plurality of ward-bearing members located between the said plates, some of the 110 said wards being in locking engagement with the said notched plate, and a key adapted to release the said locking engagement, one of the said plates having guides adapted to guide the said key.

7. The combination of a casing having a plurality of sleeves or collars, a reciprocable locking member located therein and bearing a rack, a rotatable member located therein and bearing teeth adapted to engage the 120 said rack and to reciprocate the said locking member when the said rotatable member is rotarily reciprocated, a central arbor in fixed relation to the said casing, a casing 125 in fixed relation to the said rotatable member and containing a notched plate, a pair of plates in fixed relation to the said arbor, a plurality of ward-bearing members located between the said plates, some of the said 130 wards being in locking engagement with

the said notched plate, a key adapted to release the said locking engagement, and a button to hold the said key in unlocking position.

8. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a notched plate, a pair of plates in fixed relation to the said arbor, a plurality of ward-bearing members located between the said plates, some of the said wards being in locking engagement with the said notched plate, a key adapted to release the said locking engagement, and a rotatable button adapted to hold the said key in unlocking position.

9. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a notched plate, a pair of plates in fixed relation to the said arbor, a plurality of ward-bearing members located between the said plates, some of the said wards being in locking engagement with the said notched plate, and a key adapted to release the said locking engagement, there being holes in one of the said plates for the insertion of the said key, and the said key bearing pins adapted to pass through the said holes, and a dust plate adapted to cover the said holes from the admission of dust and mounted to be rotated to uncover the said holes for the insertion of the said key.

10. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a notched plate, a pair of plates in fixed relation to the said arbor, a plurality of ward-bearing members located between the said plates, some of the said wards being in locking engagement with the said notched plate, and a key adapted to release the said locking engagement, one of the said plates having holes for the inser-

tion of the said key, and the said key bearing pins adapted to pass through the said holes, and one of the said plates having guides for the said key, and a dustplate adapted to cover the said holes from the admission of dust and mounted to be rotated to uncover the said holes for the insertion of the said key, and the said dustplate having slots through which the said guides project.

11. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a notched plate, a pair of plates in fixed relation to the said arbor, a plurality of ward-bearing members located between the said plates, some of the said wards being in locking engagement with the said notched plate, a key adapted to release the said locking engagement, and a button adapted to hold the said key in unlocking position, the said key having a slot through which the said button passes to operative position and across which the same is turned to hold the said key.

12. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a notched plate, a pair of plates in fixed relation to the said arbor, a plurality of ward-bearing members located between the said plates, some of the said wards being in locking engagement with the said notched plate, and a key adapted to release the said locking engagement, the said locking member being provided with a fork adapted to engage the member to be locked.

13. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a notched plate, a pair of plates in fixed relation to the said arbor, a plurality of ward-bearing members located between the said plates, some of the said

wards being in locking engagement with the said notched plate, and a key adapted to release the said locking engagement, one of the said pairs of plates containing pockets and the other holes, and the said ward-bearing members having projections adapted to slide therein.

14. The combination of a casing having a plurality of sleeves or collars, a reciprocable locking member located therein and bearing a rack, a rotatable member located therein and bearing teeth adapted to engage the said rack and to reciprocate the said locking member when the said rotatable member is 5 rotarily reciprocated, a central arbor in fixed relation to the said casing, a casing in fixed relation to the said rotatable member and containing a notched plate, a pair of plates in fixed relation to the said arbor, a plurality 10 of ward-bearing members located between the said plates, some of the said wards being in locking engagement with the said notched plate, and a key adapted to release the said locking engagement, one of the said 15 pairs of plates containing pockets and the other holes, and the said ward-bearing members having projections adapted to slide therein, the said ward-bearing members being invertible.

15. The combination of a casing having a plurality of sleeves or collars, a reciprocable locking member located therein and bearing a rack, a rotatable member located therein and bearing teeth adapted to engage the said 20 rack and to reciprocate the said locking member when the said rotatable member is rotarily reciprocated, a central arbor in fixed relation to the said casing, a casing in fixed relation to the said rotatable member and 25 containing a notched plate, a pair of plates in fixed relation to the said arbor, a plurality of ward-bearing members located between the said plates, some of the said wards being in locking engagement with the said notched 30 plate, a key adapted to release the said locking engagement, one of the said pairs of plates containing pockets and the other holes, and the said ward-bearing members having projections adapted to slide therein, the said ward-bearing members being invertible, whereby the same may be converted 35 from non-engaging to engaging members and vice versa, and spacing-screws by which the said pair of plates are attached to each 40 other.

16. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and 45 containing a notched plate, a pair of plates in fixed relation to the said arbor, a plurality of ward-bearing members located between the said plates, some of the said wards being in locking engagement with the said notched plate, a key adapted to release the said locking engagement, one of the said pairs of plates containing pockets and the other holes, and the said ward-bearing members having projections adapted to slide therein, the said ward-bearing members being invertible, whereby the same may be converted 50 from non-engaging to engaging members and vice versa, and spacing-screws by which the said pair of plates are attached to each other.

17. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and 55 containing a notched plate, a pair of plates in fixed relation to the said arbor, a plurality of ward-bearing members located between the said plates, some of the said wards being in locking engagement with the said notched plate, a key adapted to release the said locking engagement, one of the said pairs of plates containing pockets and the other holes, and the said ward-bearing members having projections adapted to slide therein, the said ward-bearing members being invertible, whereby the same may be converted 60 from non-engaging to engaging members and vice versa, and spacing-screws by which the said pair of plates are attached to each other.

18. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and 65 containing a notched plate, a pair of plates in fixed relation to the said arbor, a plurality of ward-bearing members located between the said plates, some of the said wards being in locking engagement with the said notched plate, a key adapted to release the said locking engagement, one of the said pairs of plates containing pockets and the other holes, and the said ward-bearing members having projections adapted to slide therein, the said ward-bearing members being invertible, whereby the same may be converted 70 from non-engaging to engaging members and vice versa, and spacing-screws by which the said pair of plates are attached to each other.

- said pair of plates are attached to each other, and sleeves through which the said screws pass, said sleeves being of a length equaling the distance necessary to be maintained between the said pair of plates.
19. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a shoulder and a notched plate, screws effecting attachment of said plate to said shoulder, a pair of plates in fixed relation to the said arbor, a plurality of ward-bearing members located between the said plates, some of the said wards being in locking engagement with the said notched plate, and a key adapted to release the said locking engagement.

20. The combination of a casing having a plurality of sleeves or collars, a reciprocable locking member located therein and bearing a rack, a rotatable member located therein and bearing teeth adapted to engage the said rack and to reciprocate the said locking member when the said rotatable member is rotarily reciprocated, a central arbor in fixed relation to the said casing, a casing in fixed relation to the said rotatable member and containing a shoulder and a notched plate, screws effecting attachment of said plate to said shoulder, a pair of plates in fixed relation to the said arbor, a plurality of ward-bearing members located between the said plates, some of the said wards being in locking engagement with the said notched plate, and a key adapted to release the said locking engagement.

In testimony whereof I hereunto affix my signature.

OSKAR K. KLEIN.
